John J. Geier, Clinton, and Lyle L. Sundquist, Fort Lee, N. J., assignors to Hydro-Torque, Inc., Freeport, N. Y., a corporation of New York

Application July 27, 1955, Serial No. 524,748

14 Claims. (Cl. 121—33)

This invention relates to devices for converting reciprocating motion into rotary motion and relates more particularly to portable torque-applicator devices which are fluid-pressure actuated and are of utility especially as wrenches for running up or removing nuts or bolts, or as driver units for twist drills, bits, screws and the like.

It is an object of this invention to combine, in a torque applicator device, an axially reciprocable drive means and a rotatable torque applicator shaft in such fashion as to enable the obtainment of a substantially higher average shaft torque output per unit of stroke of the reciprocable drive means than has heretofore been obtainable with such devices.

It is another object of this invention to enable the obtainment in a torque applicator device combining an axially reciprocable drive means with a rotatable torque applicator shaft, of high shaft torque output with short stroke of the reciprocable drive means.

It is a further object of this invention to provide a fluid-pressure-actuated torque applicator device in which a rotatable torque applicator shaft is driven unidirectionally, but at relatively low speed, by relatively high speed, fluid-pressure-actuated axially reciprocable drive means and is capable of delivering its torque in both directions of movement of the drive means.

It is a still further object of this invention to provide a torque applicator device of the nature aforesaid in which the output torque of the rotatable torque applicator shaft may be taken from either end of the shaft.

It is yet another object of this invention to provide a new and improved hydraulically actuated torque applicator which is compact and easily transportable and is capable of delivering a high output torque either in a clockwise or counterclockwise direction as may be required.

It is also an object of this invention to provide a new, useful and improved hydraulic wrench.

Other and further objects of this invention will appear from the following description, the accompanying drawings and the appended claims.

To the accomplishment of the foregoing ends and objects, there is provided in accordance with this invention a shaft of cylindrical contour, sometimes hereinafter referred to as a torque shaft, which is mounted for rotation on its cylinder axis and serves as a means for applying torque at either of its ends to a nut, bolt, drill, bit or other device to be rotated. Drive means, including a piston mounted for reciprocation lengthwise of the torque shaft cylinder axis, are provided for driving the torque shaft at each stroke so as to impart thereto a motion of rotation which is in the same direction, for each stroke of the piston. To this end therefore, the drive means also includes a pair of motion-converting coupling members mounted on the torque shaft and spaced from each other by the piston, and serving alternately automatically to make a driving connection between the piston and the torque shaft, first at one end of the piston and then the other, at each stroke reversal. The connection provided

by each coupling member between the piston and the torque shaft is of a nature such as to convert linear motion of the piston into rotary motion of the drive shaft. Moreover, by reason of the alternating connections provided by the coupling members the motion of the piston in either direction in its stroke will always result in a unidirectional rotation of the torque shaft which is clockwise as viewed from one end of the shaft and counterclockwise from the other.

10 The stroke of the piston is preferably relatively short and the extent or degree of rotation of the torque shaft for each stroke of the piston is preferably commensurately small. Hence, a relatively high ratio of piston strokes per unit of rotation of the torque shaft is obtainable and, by the application of a relatively high fluid-input pressure to the piston, a higher than average torque output at the torque shaft ends per unit of piston stroke, will result.

15 Reciprocation of the piston is effected, preferably by hydraulic pressure applied first to one side and then the other through the action of suitable switching valve means actuated automatically at the end of each stroke to effect the necessary pressure, and, in turn, motion reversal.

20 In the accompanying drawings which form part of the instant specification and in which like numbers refer to like parts through the several views:

25 Fig. 1 is a view in section of a double ended torque wrench embodying this invention, the view being taken along the central medial plane of the wrench;

30 Fig. 2 is a view in side elevation of the torque shaft and motion converting coupling members of the device of Fig. 1;

35 Fig. 3 is a view in section taken along the line 3—3 of Fig. 1;

95 Referring now to the embodiment of the invention shown in Figs. 1 to 11 inclusive, a piston 1 is mounted for reciprocation in a cylinder 2. Oil or other suitably working fluid for driving the piston 1 is adapted to be supplied as by a pump (not shown) and under suitable pressure to a valve chest 3 as by a feed pipe 4. A rotary two-position cylindrical valve 5 is journaled in the valve chest 3 for oscillation between a pair of terminal positions in each of which the working fluid may flow from the valve chest to the bore of the cylinder 2, for reciprocating the piston.

100 The valve 5 is provided with an axially extending feed chamber 6 which is closed at one end and is open at the

other to receive working fluid supplied to the valve chest. The valve 5 is also provided intermediate the ends of the chamber 6 with a pair of radially extending distributing passages 7 and 8, respectively. The passages 7 and 8 serve to conduct working fluid from the chamber 6 either to one or the other of a pair of diametrically opposed header compartments 9 and 10 formed in the valve chest. The header compartments are, in turn, connected by passageways 11 and 12, respectively, with the bore of the cylinder 2 at opposite sides of the piston 1. The angle of inclination of the inlet passages 7 and 8 to each other is such that positioning the valve 5 to place the passage 7, for example, in communication with the header 9, as shown in Fig. 7, will cause the passage 8 to be sealed-off by the opposing journal surface 13 of the valve chest. Thus, with the piston 1 at the end of its stroke, as in Fig. 1, working fluid may flow from the chamber 6 via the passage 7, header compartment 9 and passageway 11 to the right hand face of the piston, as viewed in Fig. 1, so as to drive the piston to the left. It follows that switching of the valve by rotating the valve 5 counterclockwise, as viewed in Fig. 7, to a position in which the distributing passage 8 is placed in communication with the header compartment 10, will cause the passage 7 to be sealed-off. Switching of the valve 5 is adapted to be accomplished automatically at the end of each stroke, by means of a spring-pressed snap-action toggle 14 flexibly connected at its one end to the piston 1 and at its other to the valve 5, as shown in Fig. 1. Both the valve chest 3 and cylinder 2 are suitably recessed to provide a tapered chamber 15 dimensioned to permit the toggle freely to oscillate between its terminal positions.

The valve 5 is also provided with an axially-extending by-pass chamber 16 which is partitioned off at one end from the chamber 6. It is also provided with a pair of radially extending by-pass passages 17 and 18, respectively, intermediate the ends of the chamber 16, and with a plurality of radially extending discharge passages 19 at the other end of the chamber 16. Four such discharge passages are shown in Fig. 8.

It will be understood that as the piston 1 moves in either direction in the bore of the cylinder 2, low pressure working fluid at the downstream or low pressure side of the piston, must be evacuated therefrom at the same time that high pressure working fluid is being supplied to the upstream or high pressure side of the piston. The passageways 11 and 12 serve reversibly as supply and discharge conduits for conducting working fluid between the cylinder bore and the respective header compartments 9 and 10, and the by-pass passages 17 and 18 serve to conduct working fluid discharged into the header compartments from the cylinder bore, into the by-pass compartment 16. Accordingly, the by-pass passages 17 and 18 are inclined to each other at a suitable angle and are suitably angularly offset relative to the distributing passages 7 and 8, so that while high pressure working fluid is being supplied to either one of the header compartments 9 and 10 from the feed chamber 6, evacuated working fluid may continuously escape from the other header compartment into the by-pass compartment 16 with its discharge passages 19.

The discharge passages 19 terminate each in a common annular sump 20 formed in the valve chest 3 and surrounding the valve 5. A passageway 21 in the valve chest 3 serves to conduct the evacuated working fluid from the sump 3 to the outside of the valve chest, and may be coupled, as by a pipe 22, to an accumulator (not shown) for repressuring and recycling in the pumping system.

The piston 1 is symmetrical about a plane normal to its stroke axis, centrally apertured and is provided with a hollow tubular piston rod 23 extending in opposite directions for equal distances from the piston plane of symmetry. Thus, as viewed in Fig. 1, the piston rod 23 is made up of right-hand and left-hand portions 24 and 25

identical with each other. The right-hand and left-hand cylinder heads 26 and 27, respectively, are suitably centrally apertured to receive slidably the piston rod portions 24 and 25, respectively. Preferably, the cylinder heads are flanged on their inside faces to provide in the cylinder bore right-hand and left-hand tubular bearing flanges, 28 and 29, respectively, which serve as extended tubular bearing surfaces for the rod portions 24 and 25, respectively, and minimize leakage of working fluid between the piston rod and cylinder heads, from the cylinder bore. In accordance with this feature of the invention, the piston 1 is of a configuration to provide in its opposite faces annular recesses 30 and 31, respectively, in which the sealing flanges 28 and 29, respectively, are telescopically received at the extremes of the piston stroke.

The cylinder heads are also flanged on their respective outer faces to provide externally right-hand and left-hand tubular spline flanges 32 and 33, respectively, whose inner circumferential peripheries are, respectively, of a configuration to provide spline lands 34 and 35, respectively, which mate with spline grooves 36 and 37, respectively, in the piston rod portions 24 and 25, respectively. Thus, the motion of the piston and its rod is confined to linear reciprocation relative to the cylinder 2, and spline flanges 32 and 33.

The external bearing flanges 32 and 33 are provided with vent openings 38 and 39, respectively, in which vent lines 40 and 41, respectively, are secured for the escape of such working fluid as may leak between the piston rod and the cylinder head apertures into the respective bores of the bearing flanges. Advantageously, the cylinder head 26 with its spline flange 32 may be detachably coupled to the cylinder 2, as by bolts 30', to permit assembly and disassembly of the parts. The bores of the tubular spline flanges 32 and 33 are capped by closure members 42 and 43 detachably firmly secured to the flanges 32 and 33, respectively, as by sets of bolts 44 and 45, respectively.

The closure members 42 and 43 are centrally apertured to provide journal bearing surfaces 46 and 47, respectively, which are coaxially aligned with each other and with the axis of reciprocation of the piston 1. Advantageously, the bearing surfaces 46 and 47 may be provided by replaceable bearing inserts 48 and 49, respectively, seated in the respective closure members and providing separate thrust bearing surfaces 50 and 51, respectively, for a purpose which will more fully appear hereinafter.

A torque shaft 53 of cylindrical contour is disposed within the bore of the piston rod 23 in sliding fit relation to the piston rod. The torque shaft is of a configuration to provide a pair of lesser diameter cylindrical end portions 54 and 55 and is of a length such that it extends at each end a suitable distance beyond the end closure members 42 and 43. The outer extremity of each end portion is formed to provide a torque applicator head of a configuration adapting it for operative connection to whatever device is to be torque driven. As here preferably embodied, the extremities of the end portions 54 and 55 are in the form of four-sided bits 56 and 57 adapted for use to drive a bolt having a recessed head, such, for example, as the bolt 59 indicated by dash-dot lines in Fig. 1.

The torque shaft is journaled for rotation in the bore of the piston rod 23 by means of the end portions 54 and 55 journaled on the bearing surfaces 46 and 47, respectively.

Motion-converting coupling members designated generally by the numerals 60 and 61 are mounted on the torque shaft end portions 54 and 55, respectively, for converting the linear reciprocating motion of the driving piston 1 into unidirectional rotary motion of the torque shaft. The coupling members 60 and 61 are of identical construction and their coaction with the torque shaft 53 is the same for one as for the other.

The coupling members 60 and 61 are of cylindrical contour and of an external diameter preferably slightly

less than that portion of the torque shaft 53 between the lesser diameter cylindrical end portions 54 and 55 so as to be receivable within the bore of the tubular piston rod 23. Each member is apertured from end to end longitudinally of its cylindrical axis so as to permit of the members 60 and 61 being journaled for limited angular movement on the torque shaft end portions 54 and 55, respectively. The member 60 is of a length axially to fit easily, but not snugly, between the right hand end, as viewed in Fig. 1, of the larger diameter portion of the torque shaft and the opposing thrust bearing surface 50 of the bearing insert 48, a similar arrangement obtaining between the coupling member 61 and the thrust bearing surface 51 at the other end of the torque shaft. The members 60 and 61 are also of a configuration to provide a pair of coaxial recesses 62 and 63, respectively, for the reception of a pair of coiled restoring springs 64 and 65, respectively, which are constructed and arranged to exercise respective restoring forces on the respective coupling members upon the torque shaft being angularly displaced relative to the coupling. Thus, assuming the coupling member 60 to be held against rotation and the torque shaft 23 to be angularly displaced in a clockwise direction as viewed from the right-hand end in Fig. 1, the coil spring 64 will be wound up and tend to rotate the coupling member 60 clockwise if the latter is released. At the other end of the torque shaft, the same rotation of the torque shaft will be counterclockwise as viewed from the left-hand end in Fig. 1, and the coil spring 65 will be wound up and tend to rotate the coupling member 61 counterclockwise upon release of the latter. To this end, therefore, the respective ends of the coil spring 64 are seated in suitable recesses 66 and 68 in the coupling member 60 and torque shaft 53, respectively and the ends of the coil spring 65 are seated in suitable recesses 67 and 69 in the coupling member 61 and torque shaft 53, respectively.

The recessed end of the coupling member 60 is of a configuration to co-act with the opposing end of the torque shaft 53 to permit limited angular displacement of the torque shaft relative to the coupling member. As here preferably embodied, the recessed end of the coupling member 60 is provided with a circular row of driving teeth 70 and the opposing end of the torque shaft is provided similarly with a circular row of driven teeth 72, the teeth in each row extending into the inter-tooth spaces in the other row and the teeth in the respective rows being equally spaced apart from each other circumferentially a distance sufficient to permit the requisite limited angular displacement of the torque shaft relative to the coupling member 60. Similarly, the recessed end of the coupling member 61 and the opposing end of the torque shaft 53 are provided with the circular rows of driving and driven teeth 71 and 73, respectively, in a corresponding relationship. It will be apparent from Figs. 1 and 2 that the driving teeth of each coupling member are normally held against the driven teeth of the torque shaft but that by reason of the spacing between the teeth in each row, either coupling member may be held against rotation and still permit the other to impart rotation to the torque shaft over a limited angular distance without interference.

A set of rollers or cam followers 74 is carried by the coupling member 60 and a corresponding set 75 by the coupling member 61. The rollers of each set are arranged in pairs of diametrically opposed rollers, the pairs of each set being equally angularly offset from each other. The rollers 74 are journaled individually on individual axles of a set of radially extending axles 76 carried fixedly by the coupling member 60 in suitable apertures therein. Similarly, the rollers 75 of the coupling member 61 are individually journaled on corresponding individual axles 77. Advantageously, the circumferential periphery of each of the coupling members 60 and 61 may be suitably recessed to provide individual recesses 78 for the rollers

74 and like recesses 79 for the rollers 75. In this way the rollers may be axially dimensioned to obtain a structural strength adequate to carry safely the maximum loading to be imposed thereon.

For the purpose of rotating the coupling members 60 and 61 alternately so as in turn to rotate the torque shaft always in the same direction, the tubular piston rod portions 24 and 25 are of a configuration at their free ends to provide at each such end a set of camming surfaces for alternate driving engagement with and disengagement from the individual sets of rollers or cam followers 74 and 75. As here preferably embodied, the piston rod portion 24, which will be hereinafter referred to as the piston cam 24, is provided at its free end with a set of inclined driving surfaces 80, one for each of the rollers or cam followers 74. Each such driving surface 80 may be of a contour to provide rapid angular acceleration and deceleration of the cam-follower rollers 74 at the start and finish of the linear stroke of the piston cam 24, and a substantially uniform angular velocity of the rollers 74 during the stroke. Each driving surface 80 is succeeded by a dwell surface 82 which, in turn, is succeeded by an escape surface 84 connecting the dwell surface with the next succeeding driving surface 80. The dwell surfaces 82 parallel the reciprocal axis of the piston cam 24. Each dwell surface is of a length which is preferably slightly less than the piston stroke such that upon the piston cam 24 moving from right to left as viewed in Fig. 5, the escape surface 84 will completely uncover the cam follower rollers 74 at substantially the end of the stroke to permit rotation, i. e., advance, of the coupling member 60 on the torque shaft end portion 54 under the action of the restoring spring 64. It will be apparent therefore that the spacing of the driving teeth 70 of the coupling member 60, and of the driven teeth 72 of the torque shaft 53 must be commensurate with the lengths of the dwell surfaces 82 so that with the coupling member 60 held stationary by the dwell surfaces 82 in one direction of the piston stroke, the torque shaft may still be rotated by the coupling member 61 being driven by the piston rod portion 25.

The piston rod portion 25, that is, piston cam 25, is of a configuration at its free end which is identical in principle but reversed in direction relative to the piston cam 24. Thus it comprises the driving surfaces 81, dwell surfaces 83 and escape surfaces 85, all functioning with respect to the cam follower rollers 75 to effect counterclockwise rotation of the coupling member 61 and torque shaft 53, as viewed from the left end of the device in Figs. 1 and 5.

In Figs. 9, 10 and 11 there is depicted stages in the relationship of the piston cams 24 and 25 to the coupling members 60 and 61, respectively in the course of one stroke of the piston. Referring to Fig. 9, it will be noted that the parts are in relative positions corresponding to those of Figs. 1 and 5, that is, with the piston 1 at the end of its stroke to the right as viewed in Fig. 1. Under these conditions, the piston cam 25 is in position to advance to the left to bring its driving surfaces 81 into driving engagement with the cam follower rollers 75. At the same time the dwell surfaces 82 of the piston cam 24 are in linear sliding engagement with the rollers 74 and hold the coupling member 60 against rotation on the torque shaft end portion 54. Rotation of the coupling members 60 and 61 corresponds to linear movement thereof in a direction at right angles to the stroke direction in the developed forms of Figs. 9, 10 and 11.

When the stroke is half completed, the coupling member 61 will have been caused to advance to the position shown in Fig. 10, the coupling member 60 remaining at rest as the rollers 74 ride the dwell surfaces 82. At the completion of the stroke, the coupling member 61 will have reached the limit of its advance and be in a position corresponding to that of the coupling member 60 at the beginning of the stroke, as shown in Fig. 11. It

will be noted from Fig. 10 that at the half-stroke position the rollers 74 are approaching the terminus of the dwell surfaces 82, and the start of the escape surfaces 84. Thus, as the stroke continues beyond the half-way mark, the escape surfaces 84 finally uncover the rollers 74. Bearing in mind that the advance of the coupling member 61 by the piston cam 24 has been accompanied by a corresponding advance of the torque shaft 23 and that the advance of the torque shaft has wound up the spring 64 (Fig. 1), it will be apparent that as soon as the escape surfaces uncover the rollers 74, the spring 64 will cause the coupling member to advance relative to the piston cam 24 to the final position shown in Fig. 11. This relative movement is made possible by the spacing of the driving teeth 70 and drive teeth 72 on the coupling member 60 and torque shaft 53, respectively, as above set forth. Thus, the piston 1 may now start on its return stroke during which the driving surfaces 80 of the piston cam 24 will advance the rollers 74 in the same direction and distance as the advance of the rollers 75. At the same time the rollers 75 will be held against the dwell surfaces 83 until they are uncovered by the escape surfaces 85, and so on.

In the device as depicted in Figs. 1 to 8, inclusive, the construction and arrangement of the piston cams and cam follower rollers is such that each stroke of the piston will effect an angular displacement of the torque shaft 53 of ninety degrees. Thus, four strokes of the piston are required for one revolution of the torque shaft. It will be apparent therefore that by the use of a relatively high pressure working fluid driving the piston at a relatively high speed, high torque output can be obtained at the torque shaft ends at a relative low torque shaft R. P. M. Moreover, either end of the torque applicator may be used to apply the torque and by merely reversing the applicator end-for-end, the torque may be reversed in direction without reversal of rotational direction of the torque shaft.

Referring now to the embodiment of this invention shown in Figs. 12 to 15 inclusive of the accompanying drawings, the torque shaft end portions 54 and 55 are provided circumferentially with helical gear portions 86 and 87, respectively. Cylindrical coupling members 88 and 89 are of a configuration internally to provide, respectively, helical gear portions 90 and 91, respectively, in toothed engagement with the gear portions 86 and 87, respectively. The coupling members 88 and 89 are adapted to be driven individually, alternately, axially outwardly of the helical gear portions 86 and 87, respectively, by the piston 1 so as to rotate the torque shaft by the action of the gear portions 90 and 91 on the gear portions 86 and 87, always in the same direction. Simultaneously with the outward driving movement of one of the coupling members, the other is adapted to be drawn inwardly by the piston and restored to starting position to complete its cycle of movement. During this retraction, the coupling member being retracted is free to rotate with the torque shaft. To this end therefore, the coupling members 88 and 89 are provided, respectively, at their respective inner ends with sets of ratchet teeth, 92 and 93, respectively. These sets are arranged in circular rows concentric with the cylinder axis of the coupling members.

Bearing sleeves 94 and 95, each of cylindrical contour, extend, respectively, axially of the coupling members 88 and 89, respectively, and terminate at their respective free ends in radially extending annular traction flanges 96 and 97, respectively. Each of the sleeves 94 and 95 is of a length axially such that the torque shaft 53 will, at all times, be telescopically received therewithin. Each sleeve is also of an internal diameter to be in sliding-fit bearing engagement with the torque shaft at all times. For purposes of assembly of the torque device, the sleeves are slotted axially to provide sets of spaced-apart flexible individual fingers 98 and 99 in the sleeves 94 and 95,

respectively. It will be apparent that by circumferentially constricting the sleeves, the effective normal outside diameter of their respective traction flanges may be reduced sufficiently to permit disengagement of the coupling members from other members, in a fashion to be more fully explained hereinafter.

The tubular piston rod 23 is provided with the pair of oppositely extending tubular splined rod portions 100 and 101 which terminate, respectively, in sets of ratchet teeth 102 and 103, respectively. These sets are respectively of a construction and arrangement to make them complementary to the sets of ratchet teeth 92 and 93, respectively.

The piston rod portions 100 and 101 are of an internal diameter over a distance inwardly from the end of each to receive the bearing sleeves 94 and 95, respectively, in annularly spaced relationship thereto, the spacing being sufficient to provide a loose sliding fit between each rod portion and its associated bearing sleeve. Moreover, the inner circumferential periphery of each rod portion is of larger diameter over a relatively narrow circumferential strip of each to provide annular recesses 102' and 103' in the rod portions 100 and 101, respectively. The bearing sleeve retracting flanges 96 and 97 extend respectively, into the recesses 102' and 103', respectively. The recesses are of a width axially of the rod portions greater than the width axially of the flanges so as to permit of an initial axial movement of the piston at the beginning of each stroke without an accompanying axial movement of the bearing sleeves.

In the operation of the device of Figs. 12-13, commencing with the piston in the position shown in Fig. 12, the initial stage of movement of the piston to the left as viewed in Fig. 12, will effect disengagement of the ratchet teeth 102 of the piston rod portion 100 from the ratchet teeth 92 of the coupling member 88. When fully disengaged the piston rod portion will have moved to the left a distance sufficient to engage the traction flange 96 of the bearing sleeve 88. Continued axial movement of the piston rod portion will draw the coupling member 88 to the left.

The same leftward movement of the piston that disengages the piston and coupling member 88 at one end will engage the piston and coupling member 89. In the engaged position the sets of ratchet teeth 93 and 103 will be interlocked. Continued movement of the piston to the left will result in the coupling member 89 being moved to the left and, since the coupling member is prevented from rotating by reason of its ratchet teeth, the gear teeth 91 in engagement with the gear teeth 87 will effect rotation of the torque shaft. It will be observed that this rotation of the torque shaft is not necessarily imparted to the coupling member 88 at the opposite end since the latter is being advanced relative to the gear portion 86 at the same rate as the coupling member 89. However, it will be apparent that the coupling member 88 is capable of rotating with the torque shaft 53 as it is moved axially by the piston rod portion 100. When the stroke is completed, the succeeding stroke to the right, as viewed in Fig. 12, will result in the coupling member 88 driving the torque shaft through the gear portion 86, the rotation being in the same direction. Advantageously, each stroke of the piston will effect a quarter turn of the torque shaft so that a relatively high piston speed is reflected in a high torque, low R. P. M. of the torque shaft, rotation always being in the same direction. Axial thrust of the torque shaft is transferred via thrust washers 104 and 105 to the thrust bearings 50 and 51, respectively, at the respective opposite ends of the torque unit.

What is claimed is:

1. A torque applicator device comprising a rotatably mounted torque applicator shaft; a tubular piston rod, a piston therefor, and a cylinder for said piston, each con-

centric with said shaft, said piston rod extending in opposite directions from said piston to provide a reciprocable double-ended drive member; means for supplying a working fluid alternately to opposite faces of said piston for driving said drive member; a pair of co-axially aligned tubular bearing flanges concentric with said shaft and extending in opposite directions from the respective opposite heads of said cylinder, said tubular bearing flanges being in splined engagement with said double-ended drive member; and, a pair of tubular coupling members concentrically mounted on said shaft for rotation relative thereto, one at each end of said drive member, for converting linear reciprocating motion of said drive member into a uni-directional rotary motion of said shaft, said motion-converting coupling members each having means co-acting with the drive member for restraining rotation of the coupling member in one direction of movement of the drive member, and said coupling members having means on each coacting with the torque applicator shaft for rotating said torque applicator shaft in response to reciprocation of said drive member.

2. A torque applicator device comprising a rotatably mounted torque-applicator shaft having provision at each of its ends for coupling the shaft to an object to be rotated; a double-ended drive member mounted for linear reciprocation in a path parallel to the rotational axis of said shaft; and, a pair of tubular coupling members concentrically rotatably mounted on said shaft, one at each end of said drive member, for converting linear reciprocating motion of said drive member into uni-directional motion of said shaft, the mounting of each coupling member on said shaft being such as to enable relative rotation of shaft and coupling member only in one direction of movement of the drive member, said coupling members having means on each coacting with the torque applicator shaft for rotating said torque applicator shaft in response to reciprocation of said drive member.

3. A torque applicator device comprising a rotatably mounted torque applicator shaft; a cylinder concentric with said shaft; a piston in said cylinder, said piston having a tubular piston rod extending in opposite directions from said piston to provide a reciprocable double-ended drive member; means for supplying a working fluid alternately to opposite faces of said piston for driving said drive member; a pair of motion-converting tubular coupling members concentrically rotatably mounted on said shaft, one at each end of said drive member; means on each end of said drive member engageable with the associated coupling members for restraining rotation of said coupling members alternately on successive strokes of said drive member; and, means on each coupling member for rotating said torque applicator shaft in response to reciprocation of said drive member.

4. A torque applicator device comprising a rotatably mounted torque applicator shaft, said shaft being of a configuration to provide a central portion and a pair of lesser diameter end portions, one at each end of the central portion, and said center portion having at its ends a pair of circular rows of driven teeth, one row at each end; a tubular piston rod slidably mounted on said central portion, a piston therefor, and a cylinder for said piston, each concentric with said shaft, said piston rod extending in opposite directions from said piston to provide with said piston a reciprocable double-ended drive member, the respective opposite ends of said drive member being of a configuration to provide at each of its ends a set of camming surfaces; means for supplying a working fluid alternately to opposite faces of said piston; a pair of motion-converting coupling members journaled on said lesser diameter end portions, one on each, for converting linear reciprocating motion of said drive member into a unidirectional rotary motion of said shaft, said coupling members each having a coaxial recess in the end thereof adjoining said central portion, a set of cam followers to be driven by the set of camming surfaces at the associated

end of said piston rod, and a circular row of driving teeth at its recessed end, said driving teeth extending into the intertooth spaces of the opposing row of driven teeth on said torque shaft, the spacing of the driving and the driven teeth in each of said rows being sufficient to permit limited angular displacement of the torque shaft relative to the coupling members alternately on successive strokes of the piston and, a pair of resilient means, one in each of said coaxial recesses, connecting said coupling members to said torque shaft, for restoring the respective coupling members to their starting positions relative to said torque shaft.

5. The device of claim 4 in which each end of said drive member is provided with four sets of camming surfaces and each of said coupling members is provided with a set of four cam followers.

6. The device of claim 5 in which each camming surface comprises an inclined driving surface, a dwell surface and an escape surface connecting the dwell surface with the next succeeding driving surface, said dwell surface paralleling the reciprocal axis of the torque shaft.

7. The device of claim 6 in which the cam followers of each set are in the form of rollers arranged in pairs of diametrically opposed rollers, the pairs of the set being equally angularly offset from each other and the rollers being journaled individually on individual axles carried fixed by the coupling member.

8. A torque applicator device comprising a rotatably mounted torque applicator shaft, said shaft being of a configuration to provide a central portion and a pair of lesser diameter end portions, one at each end of the central portion, and said center portion having at its ends a pair of circular rows of driven teeth, one row at each end; a tubular piston rod slidably mounted on said central portion, a piston therefor, and a cylinder for said piston, each concentric with said shaft, said piston rod extending in opposite directions from said piston to provide with said piston a reciprocable double-ended drive member, the respective opposite ends of said drive member being of a configuration to provide at each of its ends a set of camming surfaces; means for supplying a working fluid alternately to opposite faces of said piston; a pair of motion-converting coupling members journaled on said lesser diameter end portions, one on each, for converting linear reciprocating motion of said drive member into a unidirectional rotary motion of said shaft, said coupling members each having a set of cam followers to be driven by the set of camming surfaces at the associated end of said piston rod, and a circular row of driving teeth extending into the intertooth spaces of the opposing row of driven teeth on said torque shaft, the spacing of the driving and the driven teeth in each of said rows being sufficient to permit limited angular displacement of the torque shaft relative to the coupling members alternately on successive strokes of the piston and, a pair of resilient means, one for each of said coupling members, connecting said coupling members to said torque shaft, for restoring the respective coupling members to their starting positions relative to said torque shaft.

9. A torque applicator device comprising a rotatably mounted torque applicator shaft, said shaft being of a configuration to provide a central portion and a pair of lesser diameter end portions, one at each end of said central portion, each provided circumferentially with a helical gear portion; a tubular piston rod slidably mounted on said central portion, a piston therefor, and a cylinder for said piston, each concentric with said shaft, said piston rod extending in opposite directions from said piston to provide with said piston a reciprocable double-ended drive member, the respective opposite ends of said drive member being of a configuration to provide at each of its ends a set of ratchet teeth; means for supplying a working fluid alternately to opposite faces of said piston; and, a pair of tubular motion-converting coupling members mounted on said lesser diameter end portions concen-

trically thereof, one on each, for converting linear reciprocating motion of said drive member into a unidirectional rotary motion of said shaft, said coupling members being each of a configuration to provide internally a helical gear portion in toothed engagement with the helical gear portion of its associated lesser diameter end portion, having each a set of ratchet teeth complementary to the ratchet teeth at the associated end of said drive member, and having each a traction means coupled to said drive member for limited axial movement relative thereto.

10. The device of claim 9 in which each said coupling member comprises a bearing sleeve at the ratchet end thereof, said sleeve terminating in said traction means.

11. The device of claim 10 in which said traction means is a radially extending annular flange.

12. The device of claim 9 in which said drive member is provided at each of its ends with an annular recess in its inner circumferential surface, and each said traction means is interlocked with said drive member in said recesses.

13. The device of claim 9 in which the internal diameter of the end portions of said drive member is larger than the diameter of the central portion of said shaft, the inner surface of each of said end portions being recessed

to provide an annular groove, and in which each said coupling members comprises an axially extending sleeve at its ratchet end and an annular traction flange at the free end of said sleeve, each said flange extending into the annular recess in the associated end of said drive member and each said recess being dimensioned axially of said drive member to provide for limited axial relative movement between said drive member and said coupling members.

14. The device of claim 13 in which said sleeves are each of an internal diameter such that they are in sliding-fit bearing engagement with said torque applicator shaft and in which each said sleeve comprises a set of spaced-apart flexible individual fingers.
